UNITED STATES PATENT OFFICE.

FLEMING W. MUSSETTER, OF FOSTORIA, OHIO.

PLATEN PRINTING-PRESS.

SPECIFICATION forming part of Letters Patent No. 403,365, dated May 14, 1889.

Application filed March 7, 1888. Serial No. 266,410. (No model.)

To all whom it may concern:

Be it known that I, FLEMING W. MUSSETTER, of Fostoria, in the county of Seneca and State of Ohio, have invented certain new and useful Improvements in Platen Printing-Presses; and I do hereby declare the following to be a full, clear, and exact description of the invention, such as will enable others skilled in the art to which it pertains to make and use the same.

My invention relates to improvements in platen printing-presses in which, in addition to mechanism for tilting the platen for hand-feeding, provision is made for holding the platen stationary and supplying the paper in rolls, and for automatically feeding the paper from such rolls to the platen and from thence to a cutting device, where the printed matter is severed into sheets and discharged from the machine. The inking-plate is the segment of a hollow cylinder comprising about one-third of a circle, and this plate has an oscillating movement on its axis past the rolls of the ink-fountain, and is overlapped some distance at either throw by the inking-rolls in their oscillations past and some distance beyond the form, the inking-rolls thus being supplied at either end of their stroke with ink, and in turn inking the form while passing once across the latter in either direction.

My invention also relates to details of construction hereinafter described, and pointed out in the claims.

In the accompanying drawings, Figure 1 is a side elevation. Figs. 2 and 3 are side elevations, partly in section. Fig. 4 is a plan. Fig. 5 is a rear end elevation with the bed and accompanying parts removed. Fig. 6 is a front end elevation with the platen and connected mechanism removed. Fig. 7 is a rear elevation, in detail, of the shears. Figs. 8 and 9 are side elevations, in detail, hereinafter described. Fig. 10 is an enlarged elevation of details connected with the inking-rolls. Fig. 11 is an enlarged elevation, partly in section, of a portion of lever N and attachments. Fig. 12 is an enlarged detail of the distributing-roller mechanism.

A represents the base, to which is bolted a pair of side frames, A', for supporting the platen D and attachments, driving-shaft F, crank-shaft F', and other mechanism connected directly or indirectly with the platen, feeding device, &c.

A³ is a frame detachably secured by removable bolts a' to base A and frame A'. Frame A³ supports the mechanism for feeding paper from rolls, and is, together with its attachments, removed when the paper is fed by hand.

A² is a lateral upright frame that is bolted to the base and has suitable projecting hubs, a, on which are journaled the supports or arms B of the swinging bed B', and these hubs being hollow form journal-bearings for shaft a², the axis of this shaft being coincident with the axis of the hub.

The driving-shaft F is provided, in the usual manner, with fly-wheel, driving and loose pulleys, and crank, provided the press is to be propelled by treadle and foot power, all of which are of ordinary construction, and therefore not shown.

On the driving-shaft are mounted pinions f and f', the former engaging gear f² of the crank-shaft, and the latter engaging an intermediate gear, f³, that in turn engages gear A⁴ on shaft a², the relation of parts being such that the crank-shaft makes two revolutions while gear A⁴ makes one revolution.

On the ends of the crank-shaft are mounted disks F², having crank-wrists F³ set in line with each other, to which wrists are attached so-called "side bars" or "pitmen," F⁴, for swinging the bed, to which latter the pitmen are pivotally attached. On the crank-shaft, and between the bearings thereof, are mounted cams f⁴, f⁵, and f⁶. (See Figs. 2 and 3.) Cams f⁴ and f⁵ are for tilting the platen, and cam f⁶ is for throwing in and out of gear the feed mechanism hereinafter described, one of the movements (either that of the platen or of the roll-feeding device) being stopped by the removal of parts during the operation of the other movement.

The construction and arrangement of the platen are as follows:

D² is a frame located between and rigidly secured to side frames, A', in the inclined position shown in Figs. 1 and 3. On frame D² is mounted what might be called a "sub-platen" or "frame," D', the securing-bolt d passing through rubber block d² and passing loosely through holes in frame D² and screwing into frame D', with adjusting-screw d' arranged as shown. When once frame D' is adjusted, owing to the elasticity of block d², the slight changes required in the adjustment

of frame D' to accommodate, for instance, different thicknesses of paper, are made by means of the adjusting-screws without disturbing the securing-bolt *d*. Frame D² is 5 provided with a shoulder, D³, for supporting frame D' as against a tendency of the latter to slide down the inclined surface of frame D², thus relieving the securing-bolts from lateral strain. Boxes D⁴ are secured to frame 10 D', and in these boxes are journaled the trunnions D⁵ of the platen D. The platen in its depressed position shown in Fig. 1, in which impressions are taken, rests flatwise on frame D'. For tilting the platen to the position 15 shown in Fig. 3, in which latter position the sheets of paper are placed thereon by hand, referring to Fig. 3, lever C is pivoted at *c* to the base A, and is pivoted at *c'* to link C', the latter in turn being pivoted to ears *d'* of the 20 platen. Lever C is of the bent variety shown, to avoid contact with the driving-shaft. Lever C is usually forked at the lower end, only one leg of which is shown, so that the two legs of the lever just fit inside side walls of 25 base A. This, however, is not essential, as a single lever could be rigidly attached to a rock-shaft, with the latter extending from one side frame to the other, which would insure the same steady movement as regards lateral 30 or torsional strain as would accrue from the forked lever shown. Lever C and link C' form substantially a toggle-joint, and the pivotal stud *c'* has mounted thereon roller *c*². This roller is engaged by the cam *f*⁴, by which 35 engagement the toggle-joint is moved rearward and brought to the position shown in Fig. 3, whereby the platen is elevated. For moving the toggle-joint forward to lower the platen, I provide lever C², pivoted at *c*³ to the 40 base. The upper end of this lever has a laterally-projecting wrist, on which is journaled roller *c*⁵, the latter being engaged by cam *f*⁵. Levers C and C² are connected by a strong 45 spiral spring, *c*⁴, by means of which the two rollers *c*² and *c*⁵ are held in contact with their respective cams and the toggle-joint is swayed backward and forward for elevating and depressing the platen.

Link C³ is pivoted to lever C, and bolt C⁴ 50 passes through slot C⁵ of this link in connecting the latter with lever C², thus forming a slip-joint at this end of the link. So long as spring *c*⁴ performs its functions properly this link remains substantially inoperative; 55 but if from any cause—such, for instance, as tight-fitting joints, want of proper lubrication, weakening or breaking of spring *c*⁴ from long use—link C² would operate in place of the spring, or would at least assist the latter.

Cams *f*⁴ and *f*⁵ are preferably shaped substantially as shown, whereby the greatest tension of spring *c*⁴ is had when most needed in overcoming the inertia of the platen in depressing the latter—a matter of importance 60 65 when running the press at high speed. Gripers *d*⁴ are substantially the same as hereto-

fore used, and are removable, being used only with hand-feeding.

The bed-frame aforesaid consists, essentially, of the bed proper, B', on which the 70 form B² is placed, this bed being rigidly secured to and between supports B. These supports or arms are broad at the top, and are journaled at the bottom, as aforesaid, on hub *a*. A tie-bar, B³, of large size, and a still 75 larger tie-bar, B⁴, pass through lateral holes in the bed B' and arms B with tight fits, the bed, arms, and tie-bars forming a rigid frame-work. One or more tie-rods, B⁵, are provided, connecting the lower portions of 80 arms B. Bed B' does not abut arms B, but is separated therefrom some distance, leaving room for the operation of other parts, hereinafter mentioned, from which it will be seen that the bed is supported and held directly and entirely by the two tie-bars aforesaid. Bar B⁴, outside of arms B, is reduced in size, forming trunnions, on which are respectively journaled eccentrics *b*. These eccentrics are comparatively small in diameter and have little throw, and the rear ends of pitmen F⁴ are bored large enough to fit over these eccentrics. Each eccentric is provided with an ear, *b'*, to which is pivoted rod *b*², the rods of the two eccentrics being pivoted 95 at their lower ends to short arms *b*³ of rock-shaft *b*⁴. This shaft passes through lateral holes in arms B, and is journaled therein. A hand-lever, *b*⁵, is mounted on shaft *b*⁴ outside 100 the frame, and extends forward and upward to where it is considered most convenient for the operator. The lever is secured to the shaft by means of a set-screw, so that the direction of the lever can be changed, raising or lowering the free end thereof, according to 105 the notion of the operator. Only the stub end of this lever is shown. By raising the free end of lever *b*⁵ the eccentrics *b* are turned a trifle in the direction that moves the bed rearward to avoid an impression. This part 110 of the mechanism is known as the "impression throw-off."

A stop of some kind is arranged for lever *b*⁵ to rest on in its depressed position. This stop is preferably a small eccentric, *b*⁶, secured 115 by a single bolt to the adjacent arm B. By loosening this bolt the eccentric may be turned to elevate or depress the free end of the lever to bring it where it is most accessible. After such adjustment of the stop and with the other 120 members of the throw-off in position for taking an impression, the set-screw is tightened that holds lever *b*⁵ on shaft *b*⁴. The gravity of lever *b*⁵ holds the impression throw-off "on," and the operator has only to elevate this lever 125 a few inches in operating the throw-off to avoid an impression. With this arrangement of mechanism by turning eccentric *b*⁶ a trifle in one direction or the other to elevate or depress lever *b*⁵ (this lever having previously been adjusted as aforesaid) the eccentrics *b* are turned 130 a trifle to advance or retire the bed, and thus

5 avoid the necessity of manipulating adjusting-screws d' for thicker or thinner paper. The inking-plate E comprises about the one-third of a hollow cylinder. This plate at the end is secured to heads E', the latter being journaled on bar B⁴. These heads are cut away, as shown in Fig. 2, in places to avoid contact with shaft G' and bar B³, and are cut away in other places to save metal. Shaft G' is journaled in suitable boxes connected with arms B.

10 Journaled on bar B⁴, next outside of heads E', and fastened to the latter, are segmental gears E² for operating the inking-plate. These gears engage similar gears, G², the latter being rigidly secured to shaft G'. On shaft G', and next outside of gear G², are mounted side frames, G, of the inking-rollers, these frames being keyed fast to shaft G'. A fractional gear, G³, is mounted on and keyed fast to shaft 15 G', next outside of one of the roller-frames, and preferably inside the adjacent frame B, this latter gear engaging a toothed sector, H. Sector H is mounted on shaft H' and has a laterally-projecting wrist, H², that connects 20 with pitman H⁴ for oscillating the sector, by means of which and of the connecting-gears E² and G², just described, the inking-roller frame and the inking-plates are oscillated in opposite directions, the throw of these members 25 being such that the inking-rollers overlap and travel on the inking-plates some distance at either end of the throw. In Fig. 2 the inking-plate E and the inking-rollers g are shown at the terminus of the downstroke, 30 and it will be observed that the inking-rollers are in position about midway of the inking-plate, and that the forward edge of the latter is near the line of the bed-face. At the termini of the upstrokes the inking-plate is about 35 the same distance from the upper edge of the bed, and the inking-rollers have about the same position midway of the inking-plate, as shown below. The roller-frames G have large openings G⁴ to clear cross-bars B³ and B⁴. These 40 roller-frames have radial slots G⁵ and sliding blocks G⁶, operating, respectively, in said slots, with spiral springs g' arranged radially outside the blocks to press the latter inward. One 45 of the inking-rolls is journaled at g² in levers g³, Figs. 2 and 10, these levers being pivoted at g⁴ to block G⁶.

50 Levers g⁵ are pivoted at g⁶ to levers g³, these levers, near their extremes, having holes in which the two remaining rollers g are journaled. By means of the tilting of the levers g³ and g⁵ the inking-rollers are made to conform to the curved surface of the inking-plate and to the flat surface of the form. Springs g' are of sufficient tension to give the desired 55 pressure of the inking-rolls upon the form, but are not strong enough to bear up the weight of the inking-rolls and attachments against the inking-plate when the inking mechanism is in the position shown in Fig. 2. 60 To accomplish this I provide curved levers K, pivoted at K' to arms B, the free or forward ends of these levers being provided

with supporting-springs K² and steady-pins K³. Blocks G⁶ are provided with laterally-projecting wrists, on which are respectively journaled rollers G⁷. These rollers travel on levers K and hold the inking-rollers against the inking-plates during the lower movement of these parts.

65 Guide-plates I are made fast to the respective ends of the bed B', these guide-plates being of the form shown to guide the inking-rolls in their passage between the ink-plate and form. The rear portion of plates I are utilized in mounting the ink-fountain and distributing-rolls. The ink-fountain in the main is like ordinary ink-fountains in that there is an ink-container, I', and feed-roller I², with the necessary mechanism for regulating the amount of ink that roller I² feeds from the 70 fountain. The fountain has depending arms I³, pivoted at I⁴ to plates I. Connected, preferably, with one arm, I⁴, is a rearwardly-projecting arm I⁵, that extends over shaft H'. The rear end of arm I⁵ is provided with roller 75 I⁶, the latter resting on cam h of shaft H', as shown in Fig. 1.

80 The top face of the cam h is substantially a flat surface, so that with the oscillation of the shaft H' the cam h in its movement from a horizontal position of face in either direction will tilt arm I⁵ upward, and consequently will tilt the ink-fountain forward, the gravity of arm I⁵ being sufficient to return the ink-fountain rearward. Pawl i' is pivoted at i² to the 85 adjacent plate I. This pawl engages a ratchet-wheel, i, and the latter being made fast to a trunnion of the feed-roll, with each rearward movement of the fountain the pawl engages and actuates the ratchet-wheel and feed-roll. 90 With each forward movement of the ink-fountain the feed-roll I² comes in contact with distributing-roll J and deposits ink along a narrow strip lengthwise of this roller. The plates I are provided with slots I⁷ and I⁸. 95

100 In the central slot, I⁷, is journaled the trunnion of roller J, with blocks i⁴ integral with caps i³, backing the trunnions. Frames J' fit loosely in slot I⁸, so that the frames may reciprocate endwise therein, the frames being held in their respective slots by means of cap i³, aforesaid. In each frame J' is journaled a distributing-roller, J². For reciprocating these latter rollers endwise to give a better distribution of ink on the inking-plate, 105 I provide inclines g⁸ and g⁹ on the inner faces of the roller-frames G. The arrangement of these inclines is shown more clearly in Fig. 2, these inclines being curved concentric with the axis of the roller-frame, the zero-point of 110 the respective inclines being at g¹⁰ and the highest point being respectively at g¹¹ and the opposing inclines of the two roller-frames being set in reverse order.

115 Lugs on the end of one frame J' are arranged to engage inclines g⁹, and lugs on the other frame J' are arranged to engage inclines g⁸. By means of these inclines and of the oscillations of the roller-frame the two rollers

J^2 are reciprocated endwise, and the two rollers always move in opposite directions. The inking-plate E , as it sweeps past, engages and rotates these distributing-rolls, resulting in a 5 thorough distribution of ink upon the plate.

Chase-hook e is secured by bolt e' to the top side of the bed, the bolt serving also as a fulcrum for the hook. Plate e^2 is pivoted on bolt e' , so that the plate may turn laterally. 10 The plate has an incline, e^3 , that engages the under side of the rear portion of the chase-hook. By turning plate e^2 in the one direction or the other the rear end of the chase-hook is elevated or depressed to tighten or loosen 15 the hook end on the chase, steady-pins e^4 (see Fig. 4) serving to hold the chase-hook in place laterally.

Link H^7 is pivoted at h' to the adjacent side frame, A' . This link is provided with 20 longitudinal slot H^8 and with wrist H^6 , the latter connecting with pitman H^4 for operating the latter. In slot H^5 operates the sliding box h^2 , the latter connecting with wrist h^3 , that projects laterally from gear A^4 . As gear A^4 25 makes a half-revolution for each stroke of the bed, it follows that the inking-roll and inking-plate are moved from one terminus to the other with one stroke of the bed, and are returned to the starting-point with the next 30 stroke of the bed, the inking-plate and inking-rollers, as already explained, always moving in opposite directions and overlapping at either terminus.

If instead of feeding sheets of paper by 35 hand to the platen it is desired to feed the paper from rolls, grippers d^4 and, for instance, link C' are removed, leaving the platen stationary in its depressed position. Table d^5 is also removed. Next frame A^3 , placed in 40 the position shown in Figs. 1 and 2, is secured as aforesaid. To one of wrists F^3 of the crank-shaft, and outside of pitman F^4 , is secured crank-arm L , the latter having attached wrist L' , and with this wrist are connected the 45 rack-bars L^2 and L^3 . Wrist L' is radially adjustable in slot L^4 of arm L to give the desired throw to this crank. The teeth of rack-bar L^2 engage the teeth of pinion M of the shaft M^2 . This rack-bar slides through a 50 chamber made in yoke M' , and the latter being pivoted on shaft M^2 the rack-bar is always held in the proper position relative to pinion M , so that the teeth of the rack-bar and pinion are always in mesh. On shaft M^2 55 is keyed fast a pinion, M^3 , engaging pinion m , the latter being mounted on shaft m' of feed-roller m^2 .

The roll of paper M^4 is mounted on a spindle, M^5 , and the latter operates in vertical 60 slots M^6 of standard M^7 , by means of which the roll of paper rests on roller m^2 , and the length of paper discharged from the roll for each stroke of the machine will depend on the movement of roller m^2 , regardless of the 65 size of the paper-roll. By adjusting wrist L' in slot L^4 the desired movement is transmitted to roller m^2 , and to prevent this roller

from reversing with the return-stroke of rack-bar L^2 the engaging gears M^3 and m are thrown out of mesh during such return-stroke. 70 The mechanism for accomplishing this is as follows: Next inside of the respective side pieces of frame A^3 are located rock-arms N , of the bell-crank variety, both of which are keyed fast to shaft N' ; also, a tie-rod, N^2 , extends from one rock-arm N to the other, so that the two rock-arms, tie-rod, and shaft form a rigid frame-work. About midway of tie-rod N^2 is attached a link, N^3 , for actuating 75 rock-arm N . On shaft N' are mounted loosely 80 short upright arms n , located next inside of the respective rock-arms. The upright short arms n^0 of rock-arms N have laterally-projecting lugs N^4 , (see Fig. 11,) that overlap arms n , and the latter and these lugs are 85 respectively connected by means of securing-bolts n' and adjusting-screws n^2 , by means of which arm n can be accurately adjusted toward or from lugs N^4 , and such adjustment having been made, arms n swing with rock-arms N on a common axial line. Near the 90 upper ends of arms n is journaled the aforesaid shaft M^2 , and by tilting rock-arm N gears M^3 and m are thrown in and out of mesh. During the downstroke of rack-bar 95 L^2 gears M^3 and m are in mesh, and the paper is passed off the roll and onto the platen. During the upstroke of rack-bar L^2 rock-arms N are in their depressed positions, and gears M^3 and m are consequently out of mesh, and 100 feed-roller m^2 and the paper remain at rest. For tilting rock-arms N , the following is provided: Link N^3 connects at n^3 with lever n^4 , the latter being fulcrumed on tie-bar a^4 of frame A^3 . The rear end of lever n^4 is provided with roller n^5 , and the latter travels on cam f^6 of crank-shaft F' . During the down-stroke of rack-bar L^2 lever n^4 and the connected rock-arm N are held elevated by cam f^6 , holding gears M^3 and m in mesh. During 105 the upstroke of rack-bar L^2 roller n^5 , by gravity of the connected parts, travels on the reduced side of cam f^6 , whereby rock-arms N assume their depressed position, separating gears M^3 and m . Adjusting-screws n^2 bear 110 against small metal plates n^6 , and these plates are backed by blocks of rubber, n^7 , secured in the corresponding pockets of lugs N^4 . If, in throwing gears M^3 and m in mesh opposing teeth should engage the ends of each other, 115 rubber blocks n^7 would be depressed, and no harm would accrue; also, an arm, N^0 , Fig. 11, is connected with one of arms n , so as to reach under gear m .

Arm N^0 has a longitudinal slot, through 125 which the securing-bolt passes that secures the tooth N^6 . This tooth fits between the teeth of gear m , and tooth N^6 is adjusted on arm N^0 , so as to enter between the teeth of the gear m just as the two gears are separated, so that tooth N^6 serves as a brake to hold gear m in proper position for the teeth thereof to receive in mesh the teeth of gear M^3 when the latter is again moved forward. 130

Feed-roller m^2 , at one end thereof, is provided with gear m^3 , that by means of intermediate gears, m^4 , transmits motion to gear O , which latter engages gear O' . These latter gears 5 are mounted, respectively, on the shafts of the feed-rollers P and P' , between which the paper passes as the latter is fed along toward the platen. The lower roller, P , is of considerable length, and has a series of circumferential grooves, P^2 , in which operate fingers P^3 , that prevent the paper from winding on the roll. These fingers are attached to cross-bar P^4 , that in turn is secured to the supporting-frame A^3 . The upper feed-roller, P' , has a narrow and preferably crowning face, and is located about midway lengthwise of the roller P . On the same shaft are mounted rollers or disks p , a trifle less in diameter than roller P' , so that rollers p do not act as 15 feed-rolls, but only to smooth down torn edges of the paper. Rolls p are secured to the shaft by set-screws, and are therefore adjustable lengthwise of the shaft, and are usually adjusted to travel near the edge of the paper. 20 Plate o has a pintle, o' , that rests in notches o^2 , thus forming a pivotal bearing or hinge for the plate o . The forward end of this plate rests on the roll of paper underneath the paper that is being paid off from the roll and 25 prevents such loose paper from sagging.

On plate o are adjustably secured guides o^3 , that keep the paper in line. The rear or free ends of rock-arms N are connected by cross-bar N^7 , the latter having a longitudinal slot, N^8 , in which operate bolts N^9 , for securing grippers N^{10} , to hold the paper down on the platen during and shortly after the time the impression is being taken, these grippers, of course, being elevated and depressed 35 by the movements of rock-arms N . For severing the paper into sheets after the printing is done I provide the following:

On shaft a^2 and on the end thereof opposite gear A^4 , is mounted bevel-gear a^5 , this latter 40 gear engaging a bevel-pinion, Q , mounted on shaft Q' , the latter, of course, running lengthwise of the machine. This shaft is journaled in boxes a^6 , connected with frame A^2 . The rear end of shaft Q' is provided with crank-45 disk Q^2 , the wrist of which operates in slot R' of the movable shear-blade R . This blade is pivoted at r to the stationary blade R^2 .

Rack-bar L^3 engages pinion S , the rack-bar reciprocating through yoke S' , arranged 50 substantially the same as the yoke just described with rack-bar L^2 . Pinion S is mounted on shaft S^3 , on which shaft is mounted the lower feed-roll, S^3 , this shaft bearing also gear S^4 , that engages pinion S^5 on shaft S^6 .

Shaft S^6 is mounted on levers s , and has 55 mounted thereon the upper feed-roll, s' , of the pair. This upper feed-roll consists of two narrow-faced wheels adjustably secured on shaft S^6 by set-screws, this roll being adapted 60 to bear upon the unprinted margin of the paper. Levers s are pivoted on rod a^7 on the frame A' and the gravity of these levers and

of the upper feed-roll is sufficient to bear the latter upon the paper with sufficient force, in co-operation with the lower feed-roll, to feed 70 the paper between these rolls. When rack-bar L^3 is thrust rearward and downward, the rolls S^3 and s' are actuated in the direction that passes the paper toward the shears. On the return-stroke of this rack-bar levers s are 75 tilted upward a trifle, by means hereinafter explained, not enough to separate the teeth of gears S^4 and S^5 , but enough to remove the pressure from the paper. Fulcrumed also on rod a^7 , and lying side by side with lever s , are 80 long levers s^2 , the forward ends of which are connected by links s^3 with wrists n^3 . The rear ends of levers s^2 are connected by cross-bar s^4 , over which cross-bar the paper passes. Tie-rod s^5 extends from one lever s to the 85 other, this rod being screw-threaded from end to end, and on this tie-rod are mounted thimbles s^6 , the same being threaded internally for engaging the screw-thread of the tie-rod, whereby these thimbles are adjustable lengthwise of the rod, and are made to register with the respective margins of the printed paper. 90 When by the down movement of lever n^4 the forward ends of levers s^2 are depressed, and in consequence thereof the rear ends of these 95 levers are elevated, cross-bar s^4 presses the paper up against thimble s^6 , thus clamping the thimble, after which the further upward movement of cross-bar s^4 elevates levers s and the upper feed-roll, but, as aforesaid, 100 does not throw gears S^4 and S^5 quite out of mesh, and this occurs just as the rearward movement of rack-bar L^3 commences, so that during the reverse movement of these feed-rolls they are not only separated some distance, but the paper meantime remains clamped on cross-bar s^4 close to the feed-roller, and by the upward movement of cross-bar s^4 the paper will have been raised so that it could hardly, if at all, press upon the lower 105 feed-roll, and consequently the rear movement of the rack-bar does not affect the paper.

Cross-bar A^5 , a section of which is shown in Fig. 2, rests upon a member of frame A^2 . This bar has a longitudinal slot, through 110 which the securing-bolts pass for holding guides A^6 , the latter being adjusted on either side of the paper. The paper, after it leaves the platen, is placed by hand between the lower feed-rolls and drawn along until in the 115 position to be severed by the shears, the press being usually stopped for this purpose. As the distance from the platen to the shears is not always a multiple of the lengths into which the paper is to be cut, more or less 120 slack paper is allowed between the platen and the lower feed-roll.

It is desirable to have some means of adjusting the throw of the lower feed-rolls independent of the upper feed-rolls, and this I 130 accomplish by means of a slip-joint on rack-bar L^3 . The arrangement of parts is purposely such that the lower feed-rolls will feed somewhat faster than the upper feed-rolls,

provided the slip-joint of the rack-bar L^3 were held rigid, and the lost motion at the slip-joint is adjusted to reduce and regulate the feed of the lower rolls as required. The rack-bar L^3 is connected with a wrist-block, l , the latter having a channel, l' , on the inner face thereof, through which the rack-bar may slide endwise. The forward end of this rack-bar has a head, L^5 , the same having a hole through which stud l^2 may slide easily. This stud is screwed into and remains stationary in the wrist-block l , and the outer end protrudes through head L^5 some distance and is provided with jam-nuts l^3 . These jam-nuts are set to give the lost motion necessary in regulating the feed of the lower rolls. With such construction it is evident that wrist-block l will move forward until it strikes head L^5 before moving the rack-bar L^3 forward, and on the return-stroke the wrist-block will have moved rearward until the jam-nuts strike L^5 before moving the rack-bar rearward. In other words, the lost motion of the slip-joint is first taken up before the rack-bar is actuated in either direction. Rack-bar L^3 has therefore an end movement equal to the throw of wrist L' less the lost motion of the slip-joint. Wrist L' having been adjusted to regulate the feed of the upper rolls, the lost motion of the slip-joint is by means of the jam-nuts adjusted to regulate the feed of the lower feed-rolls.

T is a register of ordinary construction for keeping account of the printed sheets of paper. This register is suitably secured to the press-frame, and is actuated by means of rod T' , the hook end T^2 of this rod striking pin T^3 of the register. Rod T' is connected with arm b^7 of shaft b^4 , the latter, it will be remembered, forming a part of the impression throw-off mechanism and oscillating with the press-bed and its supports. When, therefore, arm b^7 in moving rearward and downward, as it would have to do in avoiding an impression, rod T' is moved rearward and downward, so that it does not strike pin T^3 , and consequently the register is not actuated while the impression throw-off is operated, by reason of which only the printed sheets are counted. The forward-and-rearward movement of arms B , that carry shaft b^4 and arm b^7 is sufficient to give the requisite end motion to rod T' for actuating the register. The severed sheets of paper fall upon an inclined table, r' , the latter having a foot-board, r^2 , adjustable up and down the inclined face of the table, according to the size of the severed sheets.

The train of gearing shown at the upper left-hand corner outside the frame in Fig. 4 is in Fig. 2 shown inside the frame. Either location will answer the purpose.

What I claim is—

1. The combination, with bed for holding the form and side pieces or supports for such bed, of two tie-bars for rigidly connecting the

bed and such side supports, leaving spaces between the ends of the bed and such supports, substantially as set forth.

2. The combination of form and stationary and reciprocating distributing-rolls, ink-plate composed of a segment of a hollow cylinder, and mechanism, preferably as indicated, for oscillating such ink-plate on its axis past the distributing-rollers, substantially as set forth. 75

3. The combination, with inking-rollers, oscillating frame for carrying such inking-rollers, and pivoted levers supporting these rollers, said levers having a yielding sliding connection with the oscillating frame, of oscillating inking-plate arranged to meet and overlap the inking-rollers at the termini of the respective strokes thereof, substantially as set forth. 85

4. The combination, with oscillating ink-plate, substantially as indicated, of reciprocating distributing-rollers and inking-fountain located midway of the stroke of the inking-plate, substantially as set forth. 85

5. The combination, with inking-rollers, oscillating frame for holding the same, pivoted levers supporting these rollers, said levers having a yielding sliding connection with the oscillating frame, and oscillating inking-plate, substantially as indicated, of distributing-rolls for distributing ink to the said inking-plate with reverse movements of the latter, substantially as set forth. 95

6. The combination, with stationary and reciprocating distributing-rolls, of oscillating ink-roller frame and oscillating ink-plate, having, respectively, different axes and intergeared, so as to move simultaneously in opposite directions, substantially as set forth. 100

7. The combination, with stationary and reciprocating distributing-rolls, ink-roller frame, and ink-plate intergeared and arranged to operate simultaneously in opposite directions, of pinion mounted on the axle of the ink-roller frame, a toothed sector for engaging such pinion, and mechanism, preferably as described, for oscillating such sector, the respective movements of the latter being turned to the strokes of the bed, substantially as set forth. 105

8. The combination, with oscillating ink-roller frame bearing sliding blocks for holding the ink-rollers, of curved levers for engaging an attachment (preferably a roller) of such sliding blocks for supporting the inking-rollers during the lower part of their travel, substantially as set forth. 110

9. The combination, with roller-frame, inking-rollers, sliding blocks, and curved levers, substantially as indicated, of one or more springs connected with each curved lever for giving an upward pressure to the inking-rollers, substantially as set forth. 115

10. The combination, with ink-fountain and distributing-rolls, the latter being journaled in frames adapted to reciprocate endwise, of oscillating ink-roller frame having in-

- clined tracks adapted to engage and reciprocate the distributing-roller frame, substantially as set forth.
11. The combination, with a distributing-roller having stationary journal-boxes, and an inking-fountain adapted to move to and from such distributing-roller, of distributing-rollers having reciprocating end movements, substantially as set forth.
12. The combination, with a distributing-roller having stationary journal-bearings and ink-fountain movable to and from such distributing-roller, of reciprocating distributing-rollers and oscillating ink-roller frame, the latter bearing inclines for reciprocating such distributing-rollers, substantially as set forth.
13. The combination, with a vibrating ink-fountain, distributing-roller having stationary journal-boxes, and distributing-rollers having end movement, of inclines on the ink-roller frame, said inclines being arranged in pairs and in reverse order for reciprocating the movable distributing-rolls simultaneously in opposite directions, substantially as set forth.
14. The combination, with bed, supporting-frame, and tie-bars connecting the bed with such support, substantially as indicated, of stationary and reciprocating distributing-rolls, ink-roller frame having an independent shaft with bearings in the side supports, segmental cylindrical ink-plate journaled on one of the tie-bars, and mechanism, substantially as indicated, for oscillating the inking-roller frame and ink-plate simultaneously in opposite directions, substantially as set forth.
15. The combination, with toothed sector for operating the inking mechanism, of tilting link connected by pitman with such sector, a crank for operating the tilting link, and a sliding block mounted on the crank-wrist, said sliding block operating in the slot of the link, substantially as set forth.
16. The combination, with toothed sector, connecting-pitman, tilting link, and crank-wrist, of crank for operating such mechanism, press-driving shaft, and impressional crank-shaft, all three so connected and intergeared that two complete revolutions of the impressional crank-shaft occur during one complete revolution in the inking-mechanism crank, substantially as set forth.
17. The combination, with rock-arm for operating the impression throw-off, of a register and rod for operating the latter, said rod being connected with the said rock-arm, the arrangement of parts being substantially as indicated, whereby the register is made inoperative when the impression throw-off is in use, substantially as set forth.
18. The combination, with a platen and an adjustable frame in which the latter is supported and on which it rests during the impression, of toggle-joint for actuating the platen and cam mechanism, preferably as indicated, for operating the toggle-joint, substantially as set forth.
19. The combination, with platen, of sub-platen or frame located back of the platen, such platen and sub-platen being pivoted or hinged together, and retaining-bolts and adjusting-screws for retaining and adjusting the sub-platen with the frame of the press, substantially as set forth.
20. The combination, with co-operating feed-rolls having, respectively, broad and narrow faces, substantially as indicated, of disks mounted on the axle of the narrow-faced feed-roll and on either side of the latter, said disks being adjustable lengthwise of the axle and being less in diameter than the intervening feed-roll, substantially as set forth.
21. The combination, with rack-bars connected with a crank in common for actuating the feed mechanism and delivering paper to and from the platen, of slip-joint had on one of the rack-bars, and mechanism, preferably as described, for regulating the lost motion of such slip-joint, substantially as set forth.
22. The combination, with co-operating feed-rolls arranged the one above the other, the lower roll having stationary journal-boxes and the upper roll being mounted on tilting-lever, of a clamping device for the paper, the upper member of such clamping device being connected with the tilting-lever and the lower member rising against the upper, the parts being arranged substantially as indicated, whereby the paper is clamped and the feed-rolls separated at the same operation, substantially as set forth.
23. The combination, with feed mechanism for feeding paper to the platen, and rock-arm for throwing such feed mechanism in and out of gear, substantially as indicated, of grippers connected with a free end of such rock-arm for holding the paper on the platen, substantially as set forth.
24. The combination, with the tilting-levers and feed-rolls mounted thereon, of cam mounted on the crank-shaft for actuating such tilting-levers, and links connecting such tilting-levers with the respective feed mechanisms, all arranged substantially as indicated, whereby both sets of feed mechanism are simultaneously made operative or inoperative, substantially as set forth.
25. The combination of rock arm or lever for throwing an oscillating roll or gear in and out of mesh with the feed mechanism, said oscillating gear being held by said rock arm or lever and oscillated by a motion independent of the motion had by the rock arm or lever, substantially as set forth.
- In testimony whereof I sign this specification, in the presence of two witnesses, this 23d day of January, 1888.
